UNITED STATES PATENT OFFICE.

ISAIAH G. HATCHER, OF CLEVELAND, OHIO.

DESIGN FOR A MOLDING.

SPECIFICATION forming part of Design No. 14,988, dated May 6, 1884.

Application filed February 12, 1884. Term of patent 7 years.

To all whom it may concern:

Be it known that I, ISAIAH G. HATCHER, a citizen of the United States, residing at Cleveland, in the county of Cuyahoga and State of Ohio, have invented and produced a new and original Design for Moldings, of which the following is a specification, reference being had to the accompanying drawings, forming part thereof.

10 Figure 1 is a plan view, Fig. 2 a side elevation, Fig. 3 an end elevation, and Fig. 4 a view in perspective, of my newly-designed moldings.

The molding is triangular in cross section 15 and has a flat base. The sides are ornamented with a succession of concaved depressions running crosswise of the sides, and the depressions on the two sides so arranged that the apex of this molding runs in a sinuous 20 line, so that the base on either side shows a succession of similar concaved lines and inter-

vening points where the apex shows a sinuous line, as shown in Figs. 1 and 4.

What I claim is—

The design for a molding herein shown and described, and consisting of a molding triangular in form in cross-section, and the sides ornamented with a succession of curved depressions running crosswise of the side, joining and forming in common intermediate raised edges, and the depressions of the two sides arranged so that the apex is shown in a sinuous line, and at the base, on either side, scalloped edges, substantially as shown and described. 35

In testimony whereof I hereunto set my hand, in the presence of two subscribing witnesses, this 2d day of February, A. D. 1884.

ISAIAH G. HATCHER.
